CLIP FOR GARMENT HANGERS

Filed Feb. 21, 1936

Ephraim Cohen

UNITED STATES PATENT OFFICE

2,061,023

CLIP FOR GARMENT HANGERS

Ephraim Cohen, Baltimore, Md.

Application February 21, 1936, Serial No. 65,164

4 Claims. (Cl. 24—261)

This invention relates to a guard, clamp or clip adapted to be employed in connection with garment hangers for the purpose of preventing garments particularly dresses hung on the same from slipping and falling.

In the conventional form of garment hanger, the inclined sides constitute the support upon which a garment or dress is hung. In the case of sleeveless dresses a most serious problem is encountered in maintaining the shoulder straps of the dress on these inclined sides, resulting nearly always in the dress falling off of the hanger with a consequent soiling of the same. To retain the shoulder straps of a dress on the inclined sides of the hanger various forms of clips have been devised and widely utilized. These clips which were designed to clamp the dress on the hanger had amongst other faults one serious deficiency in that they themselves fell or slipped off the hanger thus obviously defeating their purpose.

It is accordingly the object of this invention:—

First, to provide a clip that when placed on the hanger will lock itself thereto to prevent movement thereof in either direction.

Second, to so design the clip as to permit of ready and easy attachment and removal of the same on any type and shape of hanger.

Third, to so design the clip as to make the same equally operative in its purpose irrespective of its position and manner of application to the hanger.

Fourth, to provide the clip with opposed resiliently connected arms formed on their inside surfaces with sharply knurled or serrated gripping surfaces having a definitely determined relationship to each other.

Fifth, to form the clip either of wire or flat stock of a non-corrosive metal.

Sixth, to form the clip in a suitable, novel form, of a non-metallic material.

Seventh, to form the clip in such a manner as to maintain when the same is applied to the hanger a normal relationship to the section of rod or wire forming the inclined side of the hanger.

Eighth, to so design the clip as to necessitate in the making thereof a minimum of simple manufacturing operations along with a minimum stock requirement thus rendering the cost of the clip a minimum.

Ninth, to provide a clip which can neither by catching on the fibres or threads or by staining the fabric injure fine and expensive garments, and

Tenth, to so form the clip as to prevent accidental removal thereof from the hanger.

These and other objects and features of the in-

vention will appear more fully from the accompanying description and drawing and will be particularly pointed out in the claims.

In the drawing:—

Fig. 1 is an elevation of a garment hanger with a dress thereon that is held in place upon the hanger by two clips of my invention;

Fig. 2 illustrates in a front elevation one form of clip;

Fig. 3 is a side elevation of the clip of Fig. 2; 10

Fig. 4 shows the clip of Fig. 2 at one stage in the forming thereof;

Fig. 5 is a modification in side elevation of the clip shown in Fig. 2;

Figs. 6 and 7 illustrate a still further modification of the type of clip shown in Fig. 2; 15

Fig. 8 is an elevational view of a different form of clip;

Fig. 9 is a sectional view thereof taken on line 20

9—9, Fig. 8;

Fig. 10 shows in front elevation, and Fig. 11 in side elevation a clip similar to that of Fig. 2, but formed of flat strip stock;

Fig. 12 shows the clip of Fig. 10 at one stage in the forming thereof; 25

Fig. 13 is a modification in front elevation;

Fig. 14 shows in front elevation, and Fig. 15 in side elevation a still further modified form of clip;

Fig. 16 shows in side elevation, and Fig. 17 in front elevation another modification of clip 30 formed of flat stock;

Fig. 18 shows the clip of Fig. 17 at one stage in the forming thereof;

Fig. 19 is a front elevation and Fig. 20 a side elevation of a form of clip made of a non-metallic 35 material;

Fig. 21 shows a side view of a clip such as shown in Fig. 3, applied to a hanger of non-circular section, such as a wood hanger.

The hanger illustrated in Fig. 1 is made of 40 heavy wire and is of conventional design comprising a base B and inclined sides A—A on which are hung the shoulder straps C of a dress D. With the dress hanging evenly on the hanger there is applied to each of the inclined sides A 45 a clip 18 which acts as a stop or guard to prevent slipping of the shoulder straps C on said inclined sides, in the manner clearly obvious.

The clip 18 shown in detail in Figs. 2, 3 and 4 is formed of a metallic wire stock of any suitable 50 cross-sectional shape. The wire is preferably of a resilient or springy character and must be non-corroding; such wire being either of a suitable plated (nickel, chromium, etc.) steel, brass or alloy metal or of a non-plated non-corroding 55

metal such as stainless steel, brass or other alloy. Referring to Fig. 4, it will be seen that the clip 10 is formed of a single length of wire bent to form two equal sections 11 and 12, the ends 13 and 14 being so arranged in abutting relation to form the shoulders 15. Portions of the sections 11 and 12 are provided with sharp serrations, the serrations 16—17 on the section 11 being inclined in an opposite direction to the serrations 18—19 on the section 12 for a purpose to be hereinafter described. The sections 11 and 12 are then bent into opposed relation to form the clamping arms or gripping elements 20 and 21 of the clip, with the arm 21 being slightly longer than the arm 20 to facilitate the application of the clip 10 on the wire A, and the arm 20 provided with an intermediate arcuate portion 22 to accommodate the side A of the hanger. The upper looped portion of the clip connecting the arms 20 and 21 shown in dotted lines in Fig. 2 are bent outwardly to form the shoulders 23. It will be noted that the shoulders 15 and 23 are substantially equally spaced from the center of the arcuate portion 22. Preferably the upper portion of the arms 20 and 21 are arranged close together as shown in Fig. 3 whereby when the clip 10 is attached to the side A there will be no possibility of the clip being pushed beyond the arcuate portion 22.

In the completed form of the clip 10 the serrations on the arms 20 and 21 are opposite to each other with the inclination of the serrations on the arm 20 being differently arranged with respect to those on the arm 21. Comparing Fig. 2 and Fig. 4 it will be observed that the serrations 16—18 on the arm 20 are inclined in an opposite direction to the corresponding serrations 18—19 on the arm 21. Thus with the clip attached to the side A of the hanger it will be seen that each of the serrations will so grip the wire A as to positively resist any movement of the clip longitudinally of the side A; the serrations 18—19 resisting movement to the right, viewing Fig. 2, and the serrations 17—18 resisting movement to the left. The distance between the serrations at the transverse center of the clip is less than the diameter of the wire A whereby when the clip is attached to the same the arms 20 and 21 will be resiliently stressed so as to provide a gripping force of said arms on the wire A of substantial great intensity. The shoulders 15 and 23 in the clip 10 act to prevent the shoulder straps C of the dress from riding over the clip in the event the hanger should become tilted. Inasmuch as there are shoulders at each end and at each side of the clip 10, it is immaterial in what manner and in what position the clip is applied to the hanger. Preferably the clip should be attached to the side A in the plane of the hanger.

The clip 100 shown in side elevation in Fig. 5 is identical in all respects with that described above with reference to the clip 10 except that the arm 121 is provided with an arcuate portion 122a corresponding to the arcuate portion 122 to provide a seat for the side A. In this form the distance between the serrations 118—119 is less than the diameter of the side A so that the arms 120—121 will be resiliently stressed to provide a gripping force on the side A. As in the clip 10, the clip 100 is formed with the shoulders 115 and 123.

In Figs. 6 and 7, the wire clip 200 is of a form similar to that shown in Figs. 2, 3 and 4. In this case the parallel sections of the wire forming the arms 220 and 221 are spaced apart, with the sections in the arm 221 spaced apart a greater dis-

tance than the sections in the arm 220. As in the clip 10, the arm 220 in the clip 200 is provided with an arcuate portion 222 identical with the arcuate portion 22, and formed on the opposed surfaces of the wire sections of the arms 220 and 221 are like serrations 216—217 and 218—219. The clip 200 is provided at each of the corners thereof with shoulders 223 (at the top) and 215 (at the bottom). It is to be understood that both of the arms 220—221 may be provided with opposed arcuate portions as illustrated in Fig. 5, if so desired.

In Figs. 8 and 9 a somewhat different form of clip 300 is illustrated. In this case the clip is formed of a double wire with both sections 301—302 of equal length and joined together at one end by the loop 303. The end portions of the double wire are arranged in opposed abutting relation to form arms 320 and 321, each provided with an intermediate arcuate portion 322 and 322a. The arms 320 and 321 are encompassed by the intermediate portion of the double wire bent into a circular formation 304 and so formed that the free ends of the arms 320—321 will substantially engage the same centrally thereof. The inside of the arcuate portions 322 and 322a on each of the arms 320—321 are provided with the above described form of serrations 316—317—318—319. The fixed ends of the arms 320—321 are preferably spread apart somewhat to permit the ready application of the clip 300 on the side A. While the wire sections 301—302 of the clip are shown arranged close to each other it is to be understood that the same may be spaced a substantial distance apart in order to provide for greater stability of the clip 300 on the side A. If desired each of the sections 301—302 on the circular portion 304 may be provided with laterally diverted stops or extensions to function in the same manner as the shoulders 15—23 on the clip 10, Fig. 2.

Each of the above forms of clips have been made of wire bent in any suitable manner into the shapes disclosed. While each of the clips have been shown made of wire having a circular cross-section it is apparent that other cross-sectional forms may be utilized.

In Figs. 10 to 18 inclusive there are shown various forms of clips that are made of flat metallic spring stock having noncorroding characteristics as above indicated.

The clip 400 shown in Figs. 10 and 11 is made from a stamping having the general shape shown in Fig. 12 and provided on one face thereof at spaced portions with the knurls 416—417. The intermediate portion of the stamping is widened to define shoulders 423, and one end of the stamping is similarly widened to define the shoulders 415. The stamping is bent at the widened portion to form the arms 420 and 421, with the arm 421 being slightly longer than the arm 420. The knurled portions 416—417 of the arms 420—421 are opposed to each other and are of arcuate shape as shown to receive therein the wire A, said arms being resiliently stressed when the clip is applied to the side A. This clip 400 is similar in form to the clip 10, Fig. 2 and functions in an identical manner. If desired the knurled portions 416—417 may be replaced with serrations of the type shown utilized in the clip 10. At this point it is also to be understood that the serrations on the clips shown in Figs. 2 to 9 may be replaced with knurls such as 416—417.

The clip 500 shown in Fig. 13 is of the type 75

shown in Fig. 6 and is formed of a stamping similar to that shown in Fig. 12, except that it is wider and slotted to provide the spaced sections 511—512 each of which are provided with serrated or knurled portions as above described. Both of the arms 520 and 521 may be provided with arcuate portions as in Fig. 5, or just the arm 520 may be provided with an arcuate portion 522 as in Figs. 3 and 7.

D The clip 600 shown in Figs. 14 and 15 is made of a single stamping with the ends enlarged to define the shoulders 616 and 623. The center portion is also preferably widened and bent into a cylindrical loop 622, the arms 620 and 621 of 5 the clip being bent back onto the loop 622 to define the rounded edges 601 and 602 arranged a slight distance apart, said arms being further arranged in alignment and in a plane traversing the axis of the loop 622 as clearly shown in Fig. 0 15. The interior surface of the loop 622 is knurled as at 616 in the manner as above described, the diameter of the loop being less than the diameter of the side A so that the same will exert a spring clamping action on the side A 5 when attached thereto.

The clip 700 shown in Figs. 16 and 17 is made from a stamping having the shape shown in Fig. 18, the ends of which are widened to define the shoulders 715 and 723, and so shaped as to be of widest width at the transverse center thereof. Struck out from substantially one-half of the stamping is a tongue or arm 720, that is bent outwardly and downwardly. Both the arm 720 and the center portion of the stamping are 5 arcuately curved as at 722 and 722a to receive the side A in spring clamping engagement. The inside surface of both arcuate portions 722 and 722a are serrated or knurled, the extent thereof being clearly shown by the serrated zone in Fig. 0 18. It is obvious that when the tongue or arm 720 is bent over the serrations 716 thereon will be inclined oppositely to the serrations 717, as a result of which the clip 700 will be locked against movement in either direction on the side A: the lower or unperforated part of the stamping comprises an arm 721 that coacts with the arm 720.

The form of clip 700 may be modified if desired by providing two stamped out tongues or arms to receive therebetween the side A in much the same manner as the side A is contained within the arcuate portion 622 of the clip 600, Figs. 14 and 15.

In Figs. 19 and 20 there is illustrated still another form of clip that is made of a non-metallic material such as rubber, wood, celluloid, bakelite, laminated fabric, rubberized fabric, fibre or any other suitable material having the qualities of stiffness, combined with a degree of resiliency. The clip 800 is provided with two opposed arms 820 and 821 connected together at their upper ends, the upper portions of the arms being provided with opposed arcuate portions 822 and 822a defining a seat for the side A. The inside surface of the arcuate portions 822 and 822a are respectively provided with serrations 816 and 817 arranged in diagonally opposed relation so as to increase the frictional grip of the arms on the side A. However in some cases it may not be necessary to utilize the serrations as the coefficient of friction between the non-metallic material (for example, if rubber) and the side A will be sufficiently great to hold the clip on the wire.

In line with the arms 820 and 821 is an extension 824 having a length equal to that of said arms. The ends of each of the arms and the

extension 824 are enlarged to define the shoulders 823 and 815. Preferably the diameter of the cylindrical space provided by the arcuate portions 822—822a is less than the diameter of the side A so as to provide a friction tight engagement 5 of the clip on the side A.

It is to be appreciated that while each of the above forms of clips have been shown and described for use with a conventional round wire hanger, the same are nevertheless adaptable for 10 use on wood hangers or hangers made of stock (wood or metal) having a non-circular cross-section.

In Fig. 21 there is shown in side elevation a clip 900 of the type such as the clip 10 shown in Figs. 15 2 and 3. This clip 900 is made in a larger size and is provided with a non-circular seat 922 arranged between the arms 920 and 921 which receive in clamping engagement therebetween the rectangular section A' of a wood hanger. 20

To adapt any of the above clips to metal or wood hangers made of stock having a non-circular cross-section all that is necessary in modifying the clips is to form the arcuate seat portions to a like shape. 25

Each of the various forms of clips described above are easily and quickly attached to the wire sides A of the hanger. Inasmuch as the point of attachment of the clips to the side A is intermediate their ends and the fact that there are 30 shoulders provided at each end of said clips, it is immaterial in what position they are attached to the hanger; nor does it matter if they turn around on said wire. Referring to Fig. 1, this most advantageous characteristic of the clip will 35 be readily apparent.

Furthermore with the clip attached to the hanger in its selected position the same can never in actual use accidentally move therefrom. Because of the serrations provided on the arms 40 of the clip the same will bite into the wire of the hanger, the opposed inclined serrations (or knurls) holding the clip tightly and securely in place. In actual practice it has been found that 45 only an extreme force is capable of moving the clip longitudinally of the side A. To remove the clip all that is necessary is to pull the same laterally off of the side A.

The foregoing description is directed solely to 50 towards the construction of the various forms of clips illustrated, but I desire it to be understood that I reserve the privilege of resorting to all the mechanical changes to which the device is susceptible, the invention being defined and limited 55 only by the terms of the appended claims.

I claim:—

1. A garment retainer clip for direct clamping attachment to a garment hanger comprising 60 opposed U-shaped arms connected together at one end, each arm having parallel sections with the sections of one arm spaced apart a greater distance than the sections of the other arm, seats formed on each arm section and arranged in the same transverse plane, with the seats on at least 65 one arm defining a stop to properly position the clip on the garment hanger, said seats engaging said garment hanger at four longitudinally spaced points thereon; serrations formed on said seats having a non-parallel relationship to the 70 longitudinal extent of said garment hanger and adapted to coact with the engaged surface thereof whereby to secure said clip against longitudinal movement thereon in either direction; said clip being operative for its purpose irrespective of the 75

position it may be applied to or assume relative to said garment hanger.

2. A garment retainer clip for direct clamping attachment to a garment hanger comprising opposed U-shaped arms connected together at their upper ends by a pair of oppositely extending loops each loop including a projection on a side of said clip, one of said arms being of greater width than the other of said arms and provided 5 at its lower end with a pair of oppositely projecting extensions, seats formed on said arms intermediate the ends thereof and in the same transverse plane, with the seats on at least one arm defining a stop to properly position the clip 10 on the garment hanger, said seats engaging said garment hanger at four longitudinally spaced points thereon, serrations formed on said seats having a non-parallel relationship to the longitudinal extent of said garment hanger and 15 adapted to co-act with the engaged surface thereof whereby to secure said clip against longitudinal movement thereon in either direction; said oppositely extending loops and said oppositely projecting extensions defining shoulders at the 20 corners of the clip.
3. A garment retainer clip for direct clamping attachment to a garment hanger comprising opposed U-shaped arms connected together at their upper ends by a pair of oppositely extending loops 25 each loop including a projection on a side of said clip, one of said arms having a length

greater than the other of said arms and provided at its lower end with a pair of oppositely projecting extensions; seats formed on said arms intermediate the ends thereof, at least one of said seats defining a stop to properly position said clip on said garment hanger, angularly related serrations formed on said seats adapted to co-act with the engaged surface of the garment hanger to secure said clip thereon against longitudinal movement in either direction; said oppositely extending loops and said oppositely projecting extensions defining shoulders at the 30 corners of the clip.

4. A garment retainer clip for direct clamping attachment to a garment hanger comprising opposed U-shaped arms connected together at their upper ends by a pair of loops each loop including a projection on a side of said clip, one of said arms provided at its lower end with a pair of oppositely projecting extensions, seats formed 35 on said arms intermediate the ends thereof and in the same transverse plane, with the seats on at least one arm defining a stop to properly position the clip on the garment hanger, said seats engaging said garment hanger and formed to 40 frictionally resist movement of said clip thereon; said loops at the upper end of the clip and the extensions at the lower end thereof defining shoulders at the corners of the clip.

EPHRAIM COHEN.
